UNITED STATES PATENT OFFICE

2,053,972

CIRCUIT BREAKER

Joseph W. Seaman, Lansdowne, Pa., assignor to
General Electric Company, a corporation of
New York

Application May 4, 1935, Serial No. 19,828

3 Claims. (Cl. 200—144)

My invention relates to circuit breakers, more particularly to circuit breakers provided with circuit interrupters of the compression chamber type and has for an object the provision of a 5 simple, reliable and inexpensive circuit breaker of this character.

Heretofore circuit breakers having interrupting devices of the compression chamber type have been provided with thermal releasing means 10 arranged to trip the circuit breaker upon the occurrence of an overload, and a manually operable handle for opening and closing the circuit independently of the thermal releasing means. A circuit breaker of this type, which combines the protective features of a fuse and the advantages of 15 a manually operable switch, is described and claimed in a copending application of Ludwig S. Walle, now Patent No. 2,047,842, issued July 14, 1936.

20 The circuit breaker disclosed in the above Walle patent is arranged to interrupt overload currents without the emission of flame or arc gases, and without noise, by enclosing the contacts in a sealed pressure-resistant chamber of 25 restricted volume. The contacts move within the sealed chamber so that when an arc is drawn between the separating contacts, a rapidly increasing gas pressure is generated within the chamber. This pressure may be of the order of 30 1000 pounds per square inch and since the resistance of the arc increases rapidly with pressure, the resistance of the arc becomes so great as the pressure is built up that the arc can no longer exist and it is extinguished. While this circuit 35 breaker provides satisfactory circuit interruption under various operating conditions, it has been found that when the circuit breaker is utilized to interrupt direct current circuits, there is some tendency for the arc to hang on between the contacts for an appreciable interval, which may of course be undesirable.

40 The interrupting qualities of a breaker of this type when applied to direct current circuits may be improved by increasing the effective length of 45 the gap between the contacts when the contacts are in their open circuit position, but the problem is complicated by the fact that breakers of this type, especially when applied to panelboard installations, are considerably limited so far as 50 physical dimensions are concerned. For this reason it has been found impracticable to provide the movable contact with a long enough stroke to obtain the length of gap between the contacts which is necessary for the best opera- 55 tion and accordingly, resort must be had to other

methods of increasing the effective length of the gap between the contacts.

It has heretofore been proposed in connection with various types of circuit breakers to provide means for establishing a magnetic field adjacent 5 the point of separation of the contacts, the resulting reaction between the magnetic field and the arc stream causing the arc to be attenuated to such a degree as to effect extinguishment thereof, and I have found that the application of suitable magnetic blowout means to a circuit breaker having an interrupting device of the compression chamber type will render the circuit breaker capable of quickly interrupting a direct 10 current circuit.

15 In order appreciably to affect the arc, the strength of the magnetic field must be of considerable magnitude and accordingly, resort has heretofore been had to electromagnetic means connected either in multiple circuit or in series 20 circuit relation with the contacts for producing a suitable blowout flux in connection with power switches or circuit breakers. Such electromagnetic blowout means, however, are unsuitable for application to circuit breakers of the type described in the above-identified Walle application, due principally to the losses which occur in a winding connected in circuit with the contacts 25 of the circuit breaker. Furthermore, the provision of an electromagnet winding capable of 30 withstanding the severe overload conditions to which circuit breakers of this type are subjected is prohibited by the physical dimensional limits 35 of the circuit breaker. Therefore, much is yet to be desired in a circuit breaker of this type for 35 quickly interrupting a direct current circuit and accordingly, it is a further object of my invention to provide a circuit breaker having an interrupting device of the compression chamber type provided with means for producing a strong magnetic field adjacent the point of separation of 40 the contacts.

45 In carrying out my invention in one form, I provide a circuit breaker provided with an interrupting device of the compression chamber type and with magnetic means for establishing a strong magnetic field adjacent the point of separation of the contacts. More specifically, the interrupting device comprises a sealed compression chamber for enclosing a pair of relatively movable contacts, the chamber having a volume such that high gas pressures are generated therein by the arc formed between the contacts, and the magnetic means comprises a small permanent magnet mounted adjacent the 50 55

compression chamber of sufficient strength to produce a strong magnetic field adjacent the point of separation of the contacts. The permanent magnet must be formed of special magnetic material having a high coercive force in order that the field established thereby may substantially affect the arc, and I propose to employ a magnet formed of the alloy material described and claimed in Patent No. 1,968,569 5 issued July 31, 1934 to William E. Ruder. This alloy consists of about 6% to 15% aluminum, about 12% to 30% nickel and from a fractional per cent up to about 10% cobalt, the remainder of the composition being iron. As set forth in the Ruder patent, such an alloy may have a coercive force of about 460 gilberts per centimeter. Means are also provided for manually operating the contacts between open and closed circuit position, together with current-responsive means for operating the contacts to open circuit position upon the occurrence of overload conditions.

Although I prefer to use a permanent magnet formed from the above-described alloy, I have found that a magnet formed from the alloy described in Patent No. 1,947,274 issued February 13, 1934 to William E. Ruder, will provide a satisfactory blowout flux. This alloy consists of about 6% to 15% aluminum, about 20% to 30% nickel, the remainder of the composition being iron, and has a coercive force varying from about 330 to 350 gilberts per centimeter.

For a more complete understanding of my invention, reference may now be had to the drawing in which Fig. 1 is an elevational, sectional view of a circuit breaker embodying my invention; Fig. 2 is a plan view of the circuit breaker with certain parts broken away more clearly to illustrate the parts below; Fig. 3 is a sectional view taken along the line 3—3 of Fig. 1; and Fig. 4 is a view in exploded perspective of the permanent magnet and the supporting means therefor.

Referring now to the drawing, for purposes of illustration I have shown my invention as applied to a circuit breaker of the type described and claimed in a copending application of Winfield A. Atwood, now Patent No. 2,047,815, issued July 14, 1936. The circuit breaker shown comprises a base 10 of molded insulation for supporting an operating mechanism and an arc interrupting device of the compression chamber type which interrupt-device is mounted in an enclosure 11 formed integrally with the base 10. The interrupting device is preferably of the type described and claimed in the above-mentioned Walle patent and for the purposes of the present invention, may be described as comprising a cylinder 12 formed of non-magnetic pressure-resistant material such, for example, as brass at the opposite ends of which are supported a pair of insulating bushings 13 and 14. The insulating bushing 13 forms a closure for one end of the cylinder 12 and rigidly supports a fixed contact member 15 which extends through the bushing 13 and is electrically connected to a conductor 16. Slidably journaled in the bushing 14 for reciprocal movement into abutting engagement with the fixed contact 15 is a movable contact 17, the other end of which is electrically connected to a flexible conductor 18. Suitable sealing means (not shown) are provided which cooperate with the movable contact 17 and the bushing 14 gas tightly to seal the compression chamber.

As fully explained in the above-mentioned Walle patent, when the movable contact 17 is operated to its open circuit position, an arc will be drawn between the contacts 15 and 17 and a pressure will be built up within the cylinder 12 so as quickly to extinguish the arc. However, as before mentioned, there is a tendency for the arc to hang on between the contacts when the circuit breaker is applied to direct current installations and in accordance with my invention, I provide a permanent magnet 19 made of a material having a high coercive force, such as previously referred to herein, for establishing a magnetic field adjacent the point of separation of the contacts in order to assist in quickly interrupting the circuit between the contacts 15 and 17. In order that the magnetic field established by the magnet 19 will exert a maximum displacing force on the arc, the magnet is disposed to establish a field substantially at right angles to the path of movement of the contacts. As shown, the permanent magnet 19 is substantially U-shaped and is arranged with the legs of the U disposed in a pair of apertures 20 formed in a wall of the enclosure 11, with the yoke of the U-shaped magnet resting on the portion 21 of the enclosure wall intermediate the apertures 20, the pole faces of the magnet 19 being preferably curved, as shown, to correspond to the curvature of the cylinder 12.

In order fixedly to secure the permanent magnet 19 in the position shown, I provide a bracket 22 having a portion 23 arranged to engage the yoke of the permanent magnet and a portion 24 which extends along the upper wall of the enclosure 11 and is secured thereto by a portion of the operating mechanism in a manner to be more fully described. An insulating member 25 is provided between the bracket 22 and the permanent magnet 19 in order electrically to insulate the permanent magnet from the operating mechanism of the circuit breaker.

The particular operating mechanism shown is of the type described and claimed in the above-referred to Atwood patent and for the purposes 45 of the present invention may be described as comprising a U-shaped frame 26 for supporting the operating mechanism on the base 10. Extending at right angles from the upper ends of the upright legs of the frame are a pair of outwardly extending projections 27 which are provided with ears 28 for engagement with projections 29 molded integrally with the enclosure 11. The frame 26 is secured to the base 10 in a position such that the vertical portion of the frame 55 abuts a closure member 30 for the enclosure 11.

Reciprocal longitudinal movement of the contact 17 is obtained by means of a pair of over-center springs 31, the upper ends of which are carried by a pair of projections 32 secured on opposite sides of a U-shaped operating member 33 pivotally mounted on a pin 34 carried by the frame 26. The opposite ends of the springs 31 are secured to a pin 35 extending through an aperture in the movable contact 17 near its end. Carried by the U-shaped operating member 33 is an insulated handle 36 arranged to extend through a suitable aperture 37 in the circuit breaker cover 38, and it will be seen that when the handle 36 is moved from the position shown in the drawing to 70 operate the U-shaped member 33 in a counter-clockwise direction about its pivot 34, the movable contact 17 is operated from its open circuit position to its closed circuit position with a snap action. Similarly, when the handle 36 is returned 75

to the position shown in the drawing, the movable contact 17 is moved to its open circuit position with a snap action.

In order to insure reciprocal longitudinal movement of the contact 17, a member 39 is provided which comprises two parallel legs connected together by a cross portion 40, which legs are mounted on the pivot pin 34 with their lower ends 39a pivotally secured to the pin 35. Since the lower ends 39a of the member 39 move in a curved path about the pivot 34, the opening in the movable contact member 17 through which the pin 35 extends is elongated in a vertical direction, i. e. in the direction of the pivot pin 34 so that sufficient lost motion is obtained in a vertical direction to provide for free movement of the pin 35.

As shown, the operating mechanism includes means for operating the movable contact to its open circuit position in response to overload current conditions, which means comprise a bimetallic element 41 connected in circuit with the circuit breaker contacts so as to be heated by the current passing through the breaker. Upon the occurrence of an overload, the bimetallic element 41 is heated sufficiently to flex away from a latch 42 which is supported by a tripping member 43 mounted on the pivot pin 34. As more fully described in the above-referred to Atwood patent, the tripping member 43 is provided with a portion arranged to engage the cross member 40 extending between the legs 39 and with a notched portion which is engaged by a rod, one end of which is indicated by the reference numeral 44. A compression spring 45 encircles the rod 44 and has one end normally engaging a stop member 46 cooperating with the extending portions 27 of the frame 26, the other end of the compression spring 45 being arranged to engage an enlarged portion (not shown) on the rod 44. When the latch 42 is engaged by the bimetallic element 41 as shown in the drawing, the spring 45 is restrained under compression and when the latch 42 is released, the rod 44 will be moved to the right as viewed in Figs. 1 and 2, to operate the tripping member 43 in a counterclockwise direction about its pivot 34 to engage the cross portion 40 on the member 39, which member, it will be remembered, is connected to the movable contact 17, and thereby operate the contact to its open circuit position.

As shown in Figs. 1 and 2, the portion 24 of the supporting bracket 22 is clamped between the stop member 46 and a wall of the enclosure 11 so as to secure the permanent magnet 19 in the position shown. While various shapes of permanent magnets may be employed and various arrangements for mounting the permanent magnet can be resorted to, the arrangement shown is considered highly preferable. With the permanent magnet arranged externally of the compression chamber, as shown, a single line of circuit breaker bases, compression chambers and operating mechanisms may be manufactured for both alternating current and direct current application.

In order to adapt the circuit breaker for direct current application, it is necessary only to insert the magnet 19 into the apertures 20 with the portion 23 of the bracket 22 engaging the yoke 28 of the magnet, and then to clamp the bracket to the enclosure 11 by mounting the operating mechanism and the frame 26 on the base 10. For alternating current operation, the magnet 19 and the supporting bracket 22 are simply omitted, and it will be seen that the apertures 20 detract

neither from the appearance of the circuit breaker nor from its operating characteristics.

While I have shown a particular embodiment of my invention, it will be understood, of course, that I do not wish to be limited thereto since many modifications may be made and I, therefore, contemplate by the appended claims to cover any such modifications as fall within the true spirit and scope of my invention.

What I claim as new and desire to secure by Letters Patent of the United States, is:

1. A circuit breaker for interrupting currents of short-circuit magnitude comprising a pair of relatively movable contacts, means for operating one of said contacts through a relatively short range of movement between open and closed circuit positions to provide a relatively short interrupting gap between said contacts, walls of pressure-resistant material enclosing said contacts to form a sealed compression chamber, said chamber having a volume such that high gas pressures are generated therein by the arc formed between said contacts, the diameter of said chamber being such as to permit substantial lateral movement of said arc, and means including a permanent magnet supported externally of said chamber for producing a magnetic field adjacent to said gap substantially at right angles to the path of movement of said one contact, whereby said arc is moved laterally from said gap and thereby elongated, the elongation of said arc and the high gas pressures within said chamber cooperating quickly to extinguish said arc.

2. A circuit breaker for interrupting currents of short-circuit magnitude comprising a pair of relatively movable contacts, means for operating one of said contacts between open and closed circuit positions, walls of pressure-resistant material enclosing said contacts to form a sealed compression chamber having a volume of such magnitude that high gas pressures are created by the arc when said one contact is moved from said closed to said open circuit position and means including a permanent magnet supported on an external wall of said compression chamber for producing a magnetic field substantially at right angles to the path of movement of said one contact adjacent the point of separation of said contacts.

3. A circuit breaker for interrupting currents of short-circuit magnitude comprising a pair of relatively movable contacts, means for operating one of said contacts between open and closed circuit positions, walls of pressure-resistant material enclosing said contacts to form a sealed compression chamber having a volume of such magnitude that high gas pressures are created by the arc when said one contact is moved from said closed to said open circuit position, a U-shaped permanent magnet disposed externally of said chamber with the pole faces of said magnet adjacent one of said walls, and supporting means for positioning said permanent magnet to establish a magnetic field adjacent the point of separation of said contacts.

4. A circuit breaker comprising a pair of contacts one of which is movable between open and closed circuit positions, walls of pressure-resistant material enclosing said contacts to form a sealed compression chamber having a volume of such magnitude that high gas pressures are created by the arc when said one contact is moved from said closed to said open circuit position, means for operating said one contact between said open and said closed circuit positions, means in-

- cluding a permanent magnet for establishing a magnetic field adjacent the point of separation of said contacts and means including a bracket for supporting said permanent magnet on a wall of 5 said compression chamber, said bracket being secured by a portion of said operating means.
5. A circuit breaker comprising a base having a portion forming an enclosure, said enclosure having a pair of apertures in a wall thereof, a compression chamber within said enclosure, a pair of relatively movable contacts within said compression chamber, said chamber having a volume such that high gas pressures are generated therein by the arc formed between said contacts, means 10 for operating one of said contacts between open and closed circuit positions, a portion of said operating means being disposed adjacent said apertured wall of said enclosure, a U-shaped permanent magnet arranged with the legs thereof disposed 15 in said apertures in said enclosure wall, and means clamped between said operating means and said enclosure wall for securing said permanent magnet in said apertures.
6. A circuit breaker comprising a pair of contacts one of which is movable between open and closed circuit positions, walls of pressure-resistant material enclosing said contacts to form a compression chamber, and means including a permanent magnet for producing a magnetic field ad-

jacent the point of separation of said contacts, said permanent magnet comprising an alloy consisting substantially of 6% to 15% aluminum, 12% to 30% nickel, an appreciable quantity up to about 10% cobalt with the remainder substantially iron. 5

7. A circuit breaker comprising a pair of contacts one of which is movable between open and closed circuit positions, walls of pressure-resistant material enclosing said contacts to form a compression chamber, and means including a permanent magnet for producing a magnetic field adjacent the point of separation of said contacts, said permanent magnet comprising an alloy consisting substantially of 6% to 15% aluminum, 12% to 30% nickel, with substantially the remainder 10 from the group iron and cobalt. 15

8. A circuit breaker comprising a pair of contacts one of which is movable between open and closed circuit positions, walls of pressure-resistant material enclosing said contacts to form a compression chamber, and means including a permanent magnet for producing a magnetic field adjacent the point of separation of said contacts, said permanent magnet comprising an alloy consisting substantially of about 6% to 15% aluminum, about 20% to 30% nickel, with the remainder 20 substantially iron. 25

JOSEPH W. SEAMAN.
